UNITED STATES PATENT OFFICE.

HENRY WEITZEL, OF ITHACA, WISCONSIN.

HOOP-SPLITTING MACHINE.

SPECIFICATION forming part of Letters Patent No. 335,000, dated January 26, 1886.

Application filed November 13, 1885. Serial No. 182,742. (No model.)

To all whom it may concern:

Be it known that I, HENRY WEITZEL, a citizen of the United States, and a resident of Ithaca, in the county of Richland and State of Wisconsin, have invented certain new and useful Improvements in Hoop-Splitting Machines; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of my improved hoop-splitting machine. Fig. 2 is a front view of the same. Fig. 3 is a longitudinal vertical sectional view taken on the line x-x in Fig. 2; and Fig. 4 is a detail view, in perspective, of the roller-gage for regulating the thickness of the hoops to be cut or split from the pole.

The same letters refer to the same parts in all the figures.

This invention relates to hoop-splitting machines or devices for splitting or riving hoops for coopering from poles; and it has for its object to provide a device of this class which shall possess superior advantages in point of simplicity, durability, and general efficiency; which shall be provided with a simple and easily-adjustable device for gaging or regulating the thickness of the hoops to be manufactured; which shall be equipped with a revolving roller to support the hoops as they pass out of the machine, and which shall be so constructed and geared as to enable it to be readily manipulated by hand or by any suitable power which may be transmitted through the medium of belts, cog-gearing, tumbling-rods, or any other suitable means.

The invention further consists in the improved construction of the splitting knives or cutters, whereby they are specially adapted to follow the grain of the wood which is to be cut, thus enabling frozen poles to be cut as easily and successfully as when not frozen, which cannot, so far as I am aware, be accomplished in hoop-splitting machines of ordinary construction. By this improved construction of the knives they are also rendered self-feeding, all as will be hereinafter fully de-

scribed, and particularly pointed out in the claims.

In the drawings hereto annexed, A designates the frame of my improved hoop-splitting machine, which is constructed of wood, and which consists of a base or sill, B, on which are mounted the uprights C C, which are connected by the cap-pieces D D, and by suitable braces, E E, having boxes or bearings for the several shafts of the machine.

F is the main shaft, which may be driven by hand or by power of any suitable kind, and in any desired manner. From the said main shaft motion is transmitted through cog-gearing or in any suitable manner to a transverse shaft, G, which is in turn geared with a shaft, H.

Suitably mounted upon the shafts G and H in such a manner as to register with each other are the knives or cutting-disks I I, which consist of flat circular sharp-edged disks having wavy or scalloped edges J J, which are arranged to mesh together, as shown clearly in Fig. 3 of the drawings. By this construction and arrangement of the cutters they will perform the work of cutting or riving the hoops in a most effective manner, and they will also serve to feed the pole which is being operated upon through the machine. They will also follow the grain of the wood with greater certainty than the smooth-edged knives which are ordinarily employed, thus increasing the excellence and value of the hoops produced.

The knives or cutters may be mounted upon their respective shafts in any suitable convenient manner.

K designates a metallic strap or bracket, one end of which is suitably attached to one of the rear uprights, C, of the frame, and the other end of which is provided with a horizontal slot, L, through which passes a bolt, M, extending through one of the front uprights of the frame, to which the front end of the strap or bracket K is thereby adjustably secured. Strap K is provided with a pair of laterally-extending arms, N N, affording bearings for a vertical roller, O, that serves as a gage or guide for the material to be operated upon, and to regulate the thickness of the hoops to be cut. The operation of this part of the invention will be readily understood. The guide-

roller, which is located slightly in front of the knives or cutters, may, by properly adjusting the strap K, be placed at any desired distance to one side of said cutters, thus gaging the 5 thickness of the hoops to be riven from a pole, which is fed through the machine in contact with the said gage or guide roller.

P P are a pair of arms or brackets, which are attached pivotally to the lower ends of the 10 rear uprights, C C, of the frame. The outer ends of the said arms are connected adjustably with the upper ends of the uprights C by means of pivoted braces Q Q, having each a series of perforations, R, for the reception of 15 the fastening bolts or pins S. The outer ends of the brackets P support a roller, T, which serves as a rest for the material passing through the machine after it passes beyond the control of the operator. It will be seen that the 20 supporting roller may be readily raised or lowered, as the case may require, by properly adjusting the braces Q.

From the foregoing description, taken in connection with the drawings hereto annexed, 25 the operation and advantages of this invention will be readily understood.

The construction is simple and inexpensive, and the advantages of the improved construction of the knives or cutters, as well as of the 30 general construction and arrangement of parts, will be readily appreciated.

The operation of the machine is easy and effective, and its manipulation does not call for skilled or educated labor.

35 I would have it understood that while the general construction and arrangement of parts herein described will be usually adhered to, I desire to reserve the right to any modifications which may be resorted to without departing 40 from the spirit of my invention.

Having thus described my invention, I claim

and desire to secure by Letters Patent of the United States—

1. In a machine for splitting hoops, the combination of a frame, a pair of transverse shafts 45 suitably geared together, and the cutters mounted upon said shafts, said cutters consisting of sharp-edged disks having wavy or scalloped edges meshing or registering together, substantially as and for the purpose 50 set forth.

2. In a machine for splitting hoops, the herein-described knives or cutters, consisting of flat sharp-edged disks having wavy or scalloped edges, substantially as and for the purpose 55 set forth.

3. In a machine for splitting hoops, the combination of a suitable frame, a pair of transverse shafts geared together, the wavy-edged cutters mounted on said shafts, and a guide or 60 gage consisting of a strap or bracket attached at the rear end of the frame, connected adjustably with the front end of the same, and having laterally-extending arms, in which is journaled a vertical roller located slightly in 65 front of the cutters, substantially as and for the purpose set forth.

4. In a machine for splitting hoops, the combination of a frame, the transverse shafts having the wavy-edged cutting-disks, the laterally-adjustable gage or guide roller, and a horizontal supporting-roller connected adjustably to the rear end of the frame by means of suitable brackets or braces, substantially as and for the purpose set forth. 70

In testimony that I claim the foregoing as my own I have hereunto affixed my signature in presence of two witnesses.

HENRY WEITZEL.

Witnesses.
